UNITED STATES PATENT OFFICE.

GEORGE H. GOVE, OF ROCKFORD, ILLINOIS.

IMPROVEMENT IN MITER-CUTTING MACHINES.

Specification forming part of Letters Patent No. 171,932, dated January 11, 1876; application filed May 10, 1875.

To all whom it may concern:

Be it known that I, GEORGE H. GOVE, of Rockford, in the county of Winnebago and State of Illinois, have invented a new and useful Improvement in Miter-Cutting Machines; and I do hereby declare that the following is a full and exact description of the same, reference being had to the accompanying drawings and to the letters of reference marked thereon.

Figure 1 is a plan or top view of my improved miter-box. Fig. 2 is an end view of the saw-guide and saw-clamp set at an angle of forty-five degrees with the bed of the machine. Fig. 3 is a side view of the saw-guide, showing the springs which press the clamp and keep the saw in position; and Fig. 4 is a top view of the quadrant detached, with one of the index-sections removed.

Similar letters of reference denote corresponding parts in all the figures.

The invention relates to a novel manner of hinging the saw-holding device, giving the same both a lateral and vertical adjustment, and in such manner that an ordinary hand-saw can be used, as hereinafter described. It also relates to the manner of adjusting and holding the saw at any required angle of the work to be operated upon, as will be explained. It further relates to the construction and arrangement of an adjustable index-plate, in combination with the locking device, whereby any inaccuracy of adjustment may be remedied, all of which will be hereinafter described.

In the accompanying drawings, A represents the bed-frame, preferably made of metal, rectangular in form, mounted upon feet A³, with holes through the same for securing to the bench or table. Upon the top of the metal bed-frame is placed and secured to said frame a wood facing, B, to prevent the teeth of the saw coming in contact with the metal after the molding has been severed. A¹ is a rest or stop standing at a vertical right angle with the face B, and against which the piece to be mitered rests. C is a post made from round iron, having two right-angled flat surfaces extending the whole of the length, and placed with the angled corner toward the bed of the machine. C' is an ear secured to the back side of frame A, and provided with a suitable

socket for the reception of the upright post C, which is held in position by set-screw c. d is an eared socket-piece or hinge, which is made to fit upon and swing around the upright C. To the ear of the socket-piece d is secured, by bolts, screws, or otherwise, the saw-guide D'. On the top of the saw-guide is secured a metal plate b, having ears b¹ b¹ b² b², the ears b² having lips or projections, which reach over and rest upon the face of the index-plate, thus holding the saw-guide in position vertically. Longitudinally between ears b¹ b², and pivoted to b¹, is a lever, a', having a knife-edge at the end coming in contact with the index-plate, which holds the saw-guide in position laterally. The reverse end of the saw's lever a' rests upon a perpendicular spring-stop, a, which, it will be observed, keeps the knife-edge end in its place in indentations provided in the index-plate. By pressing down upon this spring end of the lever the reverse end is released from the index, and the saw-guide can be swung around and set at any desired angle. D is a spring-clamp, held in place by the bent iron D², one leg of which is secured in any suitable manner to the saw-guide D¹, the other leg supporting the spring-clamp by screws or bolts, which pass through the leg, springs E and E', and into clamp D. The springs E and E' are preferably made of flat steel, being curved in such manner that the ends rest against the clamp D. The center of the springs has perforations sufficiently large to give freedom of motion upon the retaining-bolt, and by which the tension of the spring may be regulated. F is an oblique mortise, one-half of which is made in clamp D, the other half in guide D¹, so as to enable the operator to see the molding or piece to be mitered at the point of contact with the saw. G is a section of a circle or quadrant, of which the upright C is the center, having a hub with an opening through the same to correspond with the circumferential part of upright C, upon which it is adjusted and held at any vertical point by the set-screw G'. Upon the upper surface of the quadrant or circular section G', and near the convex periphery, is a rib or flange, t, which enters a corresponding groove in the index-sections g g¹ g², the use of which will now be explained. To cut diagonally

through the grain of wood the saw must be sharp and truly filed, or the tendency is to run to one side of the true line. To obviate this difficulty I make my index-plate in sections, usually three in number. The middle or center one, for giving a square cut, can be permanently secured to the quadrant by a screw-threaded bolt passing through the rear extension, as shown, or in any other suitable manner. Sections g and g^2 are made similar to the center section g ; but, as they alone are provided with indentations for setting the saw for cutting angles, the ears have elongated holes, so that they can be moved to the right or to the left, as may be required to accommodate the variations of the saw, the flange t keeping them in position as to their movement to the front or rear. It will be understood that the saw is to be used between the rest D' and spring-clamp D.

Having now described my invention, what I claim as new, and desire to secure by Letters Patent, is—

1. The revolving saw-guide D¹, provided with the clamp D and spring E E', in combination with the locking device, whereby any desired angle may be given to the saw for operating upon the molding, substantially as described.

2. The quadrant or plate G, plate or plates $g g^1 g^2$, having a vertical adjustment upon the upright bar C, secured by the set-screw G', or its equivalent, in combination with the bed-frame A, substantially as described.

3. The saw-guide D¹, clamp D, provided with the mortise or opening F, for giving the operator a view of the work, as described, combined with the hinge d, pivoted to the upright C, all arranged and operating substantially as set forth.

This specification signed and witnessed this 3d day of April, 1875.

GEORGE H. GOVE.
